[57] CLAIM

The ornamental design for an outdoor lamp for nighttime grill cooking, as shown and described.

DESCRIPTION

FIG. 1 is a perspective view of my inventive outdoor lamp for nighttime grill cooking.

FIG. 2 is a top plan view thereof.

FIG. 3 is a bottom plan view.

FIG. 4 is a right side elevational view of the outdoor lamp.

FIG. 5 is a front elevational view thereof.

FIG. 6 is a right side elevational view thereof; and,

FIG. 7 is a back elevational view thereof.

The broken lines are shown for illustrative purposes only and form no part of the claimed design.
